UNITED STATES PATENT OFFICE.

MONROE WOODARD GRINDLE, OF SANTA ROSA, CALIFORNIA.

CONCRETE RAILROAD-TIE.

1,200,188.

Specification of Letters Patent.

Patented Oct. 3, 1916.

Application filed October 18, 1913. Serial No. 795,936.

To all whom it may concern:

Be it known that I, MONROE WOODARD GRINDLE, a citizen of the United States, residing at Santa Rosa, in the county of Sonoma and State of California, have invented an Improvement in Concrete Railroad-Ties, of which the following is a specification.

The object of my improvements are to provide a concrete railroad tie together with its mechanism that will excel all other railroad ties in strength, durability, simplicity and practical utility. These objects are attained by the mechanism shown in the accompanying drawings in which:—

15 Figure 1, is a top view of my invention showing its application to the rail and tie in its working position. Figs. 2 and 3 represent longitudinal sections of the same taken on different lines of Fig. 1.

20 Similar letters refer to similar parts throughout the several views.

In placing my improvements in their working positions as shown in Fig. 1, the rail *c*, is placed on the steel bearing *B*, at 25 right angles with the tie *A*, with the inner flange *f*, under and against the guard *C*. The hook on the steel rod *a*, is pressed over and against the outer flange *f*, of the rail *c*; the nut *d*, is then turned on the thread *e*, so 30 as to draw the rail *c*, firmly against the guard *C*, thus holding the rail *c*, safely and firmly in position for use.

The groove *g*, in the concrete, is aligned with the iron pipe *b*, and serves to permit the steel rods *a*, to be put into or to be drawn 35 out of the pipes *b*.

I am aware that prior to my invention, concrete railroad ties have been made; but—

I claim:—

A railway tie, including a concrete or 40 plastic member, metal bearings each having a central flat bearing surface proper flush with the upper surface of said plastic member, said metal bearings having downwardly and outwardly inclined portions embedded 45 and inclosed in said plastic member, metal tubular stringer-like members positioned diagonally intermediate said bearings and embedded in said plastic member, and bracing members housed within said tubular 50 members, with their terminals adapted to oppositely clamp the rail-bases, said bracing members being adapted to engage and conform to the downwardly and outwardly inclined portions of said bearings. 55

Dated and signed this 11th day of October, A. D. 1913.

MONROE WOODARD GRINDLE.
